FIG. 8.

INVENTOR:
Charles S. Emert,

UNITED STATES PATENT OFFICE.

CHARLES S. EMERT, OF PEORIA, ILLINOIS.

TAMPING MACHINE.

Application filed January 27, 1926. Serial No. 84,034.

My invention relates more particularly to machines for tamping concrete or other similar material into a mold, for the production of concrete blocks, tiles, bricks, and other similar products.

One object of my invention is the provision of a machine in which proper provision is made for uniformly feeding and distributing the material to the molds.

10 Another object of my invention is the provision of a strike-off mechanism for finishing the top face of the product of the machine, after the product has been tamped.

Another object of my invention in connection with the strike-off mechanism, is the provision of connections to reciprocate the strike-off device only at the time when this device operates upon the top face of the product of the machine.

20 Other objects of my invention will be hereinafter more fully set forth.

The novelty of my invention will be specifically pointed out herein and in the claims.

In the accompanying drawing:

25 Fig. 1, Sheet 1, is a front view of a machine embodying my invention.

Fig. 2, Sheet 1, is a side view of Fig. 1.

Fig. 3, Sheet 2, is a sectional plan view of the machine taken about on the dotted line 30 3—3 of Fig. 2.

Fig. 4, Sheet 2, is a sectional side elevation of part of the machine showing the feeding and distributing mechanism.

Fig. 5, Sheet 2, is a detail view of the 35 clutch operating mechanism for the strike-off.

Fig. 6, Sheet 3, is an enlarged detail sectional view of the driving mechanism for the drawer of the machine.

40 Fig. 7, Sheet 3, is a side view of Fig. 6.

The same numerals of reference are used to indicate identical parts in all the figures.

For purposes of illustration and to show one form of machine in which my invention 45 may be embodied, though without limiting myself to the details of construction, or arrangement of parts shown, but availing myself of all changes and modifications which may be made, and which fall within the 50 scope of the appended claims, I have shown a machine in which a suitable frame work is provided consisting of vertical members 1, front cross members 2, 3, and 4, rear cross members 5, and 6, and side cross members 7, 55 8, and 9, the frame work being provided

with suitable angularly arranged braces 10, and upon this frame work various parts of the machine are mounted.

The main driving shaft 11, mounted in suitable bearings 12, is carried by the cross members 7 at the upper part of the machine and is provided with a driving pulley 13 through which, by any suitable belt from any source of power, the proper speed and sufficient power is delivered to the shaft 11. 60

In the machine shown, the shaft 11 is provided with four cams 14, above each of which an arm 15 is mounted, each arm being provided with a roller 16 to cooperate with its cam 14. The arms 15 are fulcrumed as 70 at 17, at the rear of the machine, the forward ends of the arms engaging yokes 18 carried by the upper ends of tamping bars 19, the lower end of each bar carrying a foot 20. 75

In the position of the parts shown in Figs. 1 and 2, the cams 14 do not come in contact with rollers 16 though while the machine is operating, the cams raise the tamping bars 19 and permit them to drop by 80 gravity, the rollers 16 being brought into contact with the ends of the cams by the following mechanism.

A foot pedal 21 is provided and connected by a rod 22 with an arm 23 mounted 85 on the end of rock shaft 24 the latter being provided with a series of fingers 25, one for each tamping bar 19, the upper ends of fingers 25 engaging hardened blocks 26 carried by the tamping bars. A connecting rod 27 90 extends from the arm 23 to a segment 28 on a rock shaft 29 carried on the upper rear portion of the main frame. The rock shaft 29 carries a pair of crank arms 30 through which the fulcrum 17 extends. 95

A connecting rod 31 extends from the arm 23 to the lever 32 which carries the counter-weight 33. The fingers 25 are loosely mounted on the rock shaft 24 and are yieldingly moved by this shaft through the 100 medium of springs 34 which engages between the fingers 25 a U shaped arm 35 fixed on the shaft 24.

When the foot pedal 21 is depressed by the operator, the rock shaft 24 is moved and 105 the arm 35 subjects one set of springs 34 to compression to disengage fingers 25 from the tamping bars 19 and at the same time, the shaft 29 is rocked to move the fulcrum 17 rearwardly and downwardly to bring the 110

rollers 16 into contact with the points of the cams 14 which successively pick up the arms 15 and slightly raise the tamping bars 19, releasing fingers 25 whereupon, as the 5 cams 14 travel beyond the rollers 16, the tamping bars drop to perform the tamping operation.

On the release of the pedal 21 the counter-weight 33 moves the rock shaft to the position shown in Fig. 2 and as the tamping bars 10 are successively raised, the fingers 25 reengage the blocks 26 to hold the tamping bars elevated.

The material to be operated on by the machine is fed into the hopper 36, below which a drawer 37 is mounted to slide on guides 38, the latter being mounted on cross members 4 and 6, the drawer being connected by connecting rods 39 with cranks 40 on the 20 shafts 41, the latter being driven from shaft 42 by means of gearing within the housing 43.

Referring now to Figs. 6 and 7 it will be seen that shaft 41 carries a gear 44 which 25 meshes with a pinion 45 loosely mounted on shaft 42. A disc 46 is fixed on the shaft 42 and is provided with a number of openings 47 to receive the clutch pin 48 which is normally pressed toward the disc 46 by 30 the spring 49, the clutch pin 48 being provided with a disengaging finger 50 which is adapted to be operated by the clutch throw-out 51 which is carried by the shaft 52 and operated by the crank arm 53, the latter being normally held in a position to cause the 35 engagement of the throw-out finger 51 with the disengaging finger 50 by means of a coil spring 54 which is adjustably attached to the guide 38 by means of an eye-bolt 55.

40 The disc 46 is provided with a hardened plate 56 and the pinion 45 is held in operative relation to this disc by a ball thrust bearing 57.

Referring now to Figs. 1, 2 and 3, the 45 crank arm 53 is provided with an operating rod 58 which extends through the front vertical member of the frame within easy reach of the operator.

To drive the various parts of the machine 50 the main shaft 11 carries a sprocket 59 which, through the medium of chain 60, drives a sprocket 61 on shaft 62, the sprocket 61 being loose on the shaft and being adapted to engage the latter through the dental 55 clutch 63 which is provided with a shifter 64 which extends forward to within easy reach of the operator.

A second sprocket 65 is carried by shaft 11 and through the medium of chain 66 60 drives a sprocket 67 on a shaft 68 mounted in the lower portion of the machine below the shaft 11. The shaft 68 carries sprockets 69, 70, and 71, the sprocket 69 driving the chain 72 which passes rearwardly to the 65 sprocket 73 which is loose on the shaft 74

and at certain times is engaged with this shaft by means of a dental clutch 75.

The sprocket 70 drives the chain 76 which passes over the sprocket 77 on the shaft 42.

The sprocket 70 is provided for use in 75 driving a stripper or other suitable molding machine in which the product is formed, though such stripper or mold constituting no part of my present invention, is not shown.

The shaft 74 carries an eccentric 78, shown more clearly in Fig. 3, the latter having a strap 79 and rod 80 which extends to the ball and socket joint 81 of the bell-crank 82 from which a connecting rod 83 extends 80 to the strike-off 84, which will be later described.

The shaft 62 carries a relatively large sprocket 85 which, through the chain 86 drives a sprocket 87 on the distributing 85 shaft 88, this shaft being mounted across the forward part of the machine at the delivery portion of the hopper 36. The shaft 88 carries a pair of discs 89 and between these discs a pair of blades or paddles 90 90 are mounted, this portion of the construction being a part of the distributing section of the machine.

The shaft 62 also carries an eccentric 91 which is provided with a strap 92, from 95 which the connecting rods 93 extend to a pivot bar 94, the latter being carried by brackets 95 forming a part of the feeder slide which comprises the plate 96, shown more clearly in Fig. 4, supporting rails 97, 100 and outside rails 98. The rails 97 ride on rollers 99 carried by brackets 100 while the outside rails 98 are guided in supports 101 carried by the sides of the hopper 36.

The drawer 37 carries an angularly shaped 105 plate 102 (Fig. 4) which travels, when the drawer is in the position shown in Fig. 4, to near the forward edge of a plate 103 which is mounted across the upper surface of two rails 38, the plate 102 forming a table 110 above which the paddles 90 operate.

The forward end of drawer 37 is provided with a cross plate 104 and an angle 105 is mounted across the upper edge of the plate, this angle serving as an abutment for a pair 115 of springs 106 which bear against the upper surface of strike-off 84 to hold the latter yieldingly against the upper face of the rails 38, a pair of links 107, shown more clearly in Fig. 3 are pivoted to the strike-off 84 and extend rearwardly and are pivoted to side rails of the drawer 37.

Referring now to Figs. 1, 3, 4, and 5, the dental clutch 75 on the shaft 74 is moved by a yoke 108 carried by a bracket 109 the lower 125 end of the yoke being connected by rod 110 to a lever 111 which carries a roller 112 and is pivoted as at 113 to a bracket 114 which is connected to one of the rails 38, the roller 112 lying against a cam 115 carried by the 130

shaft 41 outside of the gear housing 43. A spring 116 is connected to the end of the lever 111 and to the rear cross member 6 to normally move the parts to engage the dental clutch 75 with the sprocket 73, the cam 115 being provided to hold the clutch 75 disengaged during about a half of its revolution.

Any suitable molding machine which, as before stated, is not a part of my present invention and is not shown, is mounted below the tamping bars 19 and in such a relation to the rails 38, that the upper surface of the mold cavity is flush with the upper surface of the rails 38 and the forward face of the mold cavity is in line with the plate 104 of the drawer 37 when the latter is extended as shown in the drawings.

The operation of the machine is as follows, assuming a proper driving connection to the pulley 13 and a supply of material in the hopper 36. The operator first engages the clutch 63 by means of the clutch lever 64, this engagement setting the shaft 62 in rotation and reciprocating the slide 96 and rotating the shaft 88. The slide 96 forces the material of the hopper into the path of the paddles 90 which delivers this material in substantially equal amounts to both the forward and rear portions of the mold. As soon as the delivery of the material to the mold begins, the operator presses the foot pedal 21 which, through the mechanism and connection before described starts the operation of the tamping bars 19, which operation is continued until the mold has been filled with the material and the latter properly tamped. The operator now removes his foot from the pedal 21, disengages the clutch 63, and pushes the rod 58 towards the rear of the machine thereby moving the finger 51 to the position shown in Fig. 7 and permitting the spring 49 to cause the engagement of clutch pin 48 with one of the holes 47 in the disc 46. This starts the shaft 41 and imparts to it one half revolution. The one half revolution of shaft 41 moves the drawer 37 from the position shown in the drawings to a position about in line with the front vertical members of the frame, and as soon as this shaft 41 starts its half revolution the cam 115 moves out of contact of roller 112 and permits the spring 116 to cause the engagement of the clutch 75 with the sprocket 73, to rotate the shaft 74 and through its eccentric and the connections extending to the strike-off 84, reciprocate this strike-off as the drawer 37 travels toward the rear of the machine. This movement of the strike-off accomplishes the finishing of the upper surface of the block which has been tamped and the strike-off and the plate 104 carries back into the machine and upon the plate 103 any surplus material which had been delivered into the

mold. At the end of the half revolution of the shaft 41 the clutch 75 is disengaged to stop the strike-off 84, and after the block has been taken from the mold, and the mold closed, the operator again presses rearwardly on rod 58, which again permits the engagement of the gearing to impart another half revolution to shaft 41 which extends the drawer to the position shown in the drawings, the angle plate 102 carrying the surplus material forward again and delivering it into the mold, whereupon the operator again engages the clutch 63 which, as previously described causes the delivery of additional material to the mold, and during this delivery the foot pedal 21 is again depressed, to operate the tamping bars, these processes being repeated for each block made.

The speed of the shaft 88 is such that a part of the material handled by the paddles 90 is thrown forward so that it falls in the front portion of the mold to fill this portion equally with the back portion so that the finished block will be of uniform texture.

By delivering the material in comparatively small amounts by means of the slide 96, uniformity of texture of the block is maintained from the bottom to the top by reason of the fact of the tamping process continues during the filling of the mold, the result of this uniformity from front to back as well as top to bottom is a much higher quality of product, and in addition the machine may be operated to produce a greater number of blocks in a given time than machines which have been heretofore built.

Having thus fully described my invention, I claim:

1. In a tamping machine the combination of tamping members, means for operating the tamping members, a hopper, means for delivering material from the hopper, and means for distributing the material to be operated upon by the tamping members during the operation of the latter.

2. In a tamping machine the combination of tamping members, means for operating the tamping members, a hopper, means for delivering the material from the hopper onto a plate, and a distributor for delivering the material from the plate to be operated upon by the tamping members during the operation of the latter.

3. In a tamping machine the combination of the tamping members, means for operating the tamping members, a hopper, a reciprocating feeder for delivering the material from the hopper to a plate, and a rotating distributor for moving the material from the plate and distributing it to be operated upon by the tamping members during the operation of the latter.

4. In a tamping machine the combination of tamping members, means for operating

the tamping members, a hopper, a reciprocating feeder for delivering a number of relatively small amounts of material from the hopper and a distributor for receiving 5 the amounts of material from the feeder and distributing the material to be operated upon by the tamping members during the operation of the latter while the tamping members are operating.

10 5. In a tamping machine the combination of tamping members, means for operating the tamping members, a hopper, a reciprocating feeder for delivering a number of relatively small amounts of material from 15 the hopper, and a rotating distributor for receiving the material from the feeder and distributing it under the tamping members while the latter are operating.

6. In a tamping machine the combination 20 of a material hopper, a feeder for delivering material from the hopper, a distributor for moving material and distributing it in a mold during the operation of tamping members, tamping members for operating on the 25 material, a drawer movable to a position above the top of the mold, and a strike-off carried by the drawer for finishing one face of the product of the machine.

7. In a tamping machine the combination 30 of a material hopper, a reciprocating feeder for delivering material from the hopper, a rotating distributor for moving the material and distributing it in a mold during the operation of tamping members, tamping members for operating on the material, a drawer movable to a position above the mold, a reciprocating strike-off carried 35 by the drawer, and automatic means for reciprocating the strike-off when the drawer

moves across one face of the product of the 40 machine.

8. In a tamping machine the combination of a material hopper, a reciprocating feeder for delivering a number of relatively small amounts of material from the hopper, 45 a rotating distributor for moving the material and distributing it in a mold during the operation of tamping members, tamping members for operating on the material, clutch controlled means for simultaneously 50 operating the feeder and distributor, a drawer movable to a position above the mold and a position permitting a discharge from the mold, a reciprocating strike-off carried by the drawer for finishing one face of the product of the machine, clutch controlled mechanism for moving the drawer to both positions, and automatic clutch controlled means for reciprocating the strike-off while 55 the drawer is moving across the face of the 60 product of the machine.

9. In a tamping machine the combination of a material hopper, a drawer, a plate carried by the drawer and upon which material is delivered from the hopper, a feeder for 65 delivering material from the hopper, a distributor cooperating with the plate when the drawer is extended and for distributing the material into a mold during the operation of tamping members, tamping members and means for operating them, means for moving the drawer from a position above the mold to a position permitting discharge of the product of the mold, and a strike-off carried by the drawer for finishing 70 one face of the product of the machine when the drawer is moving.

CHARLES S. EMERT.
